2 Sheets-Sheet 2

UNITED STATES PATENT OFFICE.

WILLIAM A. LORENZ, OF HARTFORD, CONNECTICUT, ASSIGNOR TO THE OTAKA FABRIC COMPANY, OF HARTFORD, CONNECTICUT, A CORPORATION OF CONNECTICUT.

PAPER CRINKLING.

Application filed November 5, 1920. Serial No. 422,006.

To all whom it may concern:

Be it known that I, WILLIAM A. LORENZ, a citizen of the United States, residing in Hartford, in the county of Hartford and State of Connecticut, have invented certain new and useful Improvements in Paper Crinkling, of which the following is a specification.

This invention relates to means for corrugating paper, and also to means for crinkling the paper crosswise of the corrugations therein. The corrugations extend longitudinally of the web and are comparatively deep, and it is one of the main objects of the invention to produce these corrugations without rupturing or unduly weakening the paper, even though the width of the corrugated web remains about the same as that of the web in its original condition.

In effecting the foregoing improvement, no devices are used for preliminarily gathering the web widthwise into flutes, but the web is fed directly to power-driven grooved rolls. The web is first moistened to such an extent as to permit it to yield widthwise to accommodate itself to the action of the corrugating rolls in forcing it into a wavy contour or form. The paper may then be subjected to one or more additional corrugating actions, by the use of additional grooved rolls, (all of the rolls having the same pitch), so that finally the paper is brought to the desired corrugated condition, the corrugations being preferably deepened as the paper passes between the rolls in each pair, and at each step becoming firmer and more set. Preferably heat is employed, partly for the purpose of diffusing the moisture more thoroughly throughout the sheet, for preparing it for subsequent corrugating pressure. The heat may be applied by at least two corrugating cylinders, and the paper eventually preferably becomes dry, or at least warm, while still passing over the corrugating rolls. The final roll in the set is used for the purpose of driving the corrugated paper against a doctor-blade, thereby crinkling the paper in transverse lines.

The corrugations may be small or large, as preferred, and according to the thickness and wetness of the paper to be corrugated.

Another feature of the invention relates

to effecting variations in the crinkling, giving alternate bands of deep and shallow wrinkles, thereby producing an ornamental configuration or pattern of crinkling, and securing other advantages. This result is secured by controlling the roll which runs upon the corrugated web in proximity to the doctor-blade to aid in crushing the web against the blade. The roll is made to move to and fro regularly, away from and towards the doctor-blade, whereby the desired variation in the crinkling is produced. When the roll is close to the blade, the wrinkles are accentuated and deep, while when the roll is remote from the blade, the wrinkles are less marked and shallow.

Other features and advantages will hereinafter appear.

In the accompanying drawings, Figure 1 is a plan of an apparatus embodying several features of the invention above referred to in one form.

Figure 2 is a sectional side elevation taken at about the line 2—2 of Figure 1.

The rotation of a supply roll 10 of paper is retarded by a weighted strap 11. From this roll the web 12 may be led up over an introductory roll 13 to a moistening apparatus comprising two rolls 14, 15, over which the web runs in succession to expose its opposite sides to the water, which is applied thereto by rolls 16, 17. Said rolls 16, 17 take up the water from distributing rolls 18, which are immersed in water 19 contained in troughs or tanks 20, supplied by pipes 21 and provided with overflow pipes 22. Each roll 18 is mounted upon an eccentric 23, to adjust it to the right relation to the companion rolls 16, 17. Each of the latter is mounted by means of arms upon a rock-shaft 25, from which extend horizontal arms 26, carrying adjustable weights 27, to regulate the pressure of the moistening rolls 16, 17 against the paper.

A gage 18^a may be employed to extend to the immersed roll 18, to graduate the amount of water which said roll picks up and distributes to the wetting rolls 16 and 17.

From the wetting apparatus, the web is led at 27^a to a longitudinally corrugating or fluting set, comprising power-driven cylinders or rolls 28, 29, 30 and 31, all having intermeshing peripheral grooves 32, for rolling the corrugations into the web. The gear

system for driving these and other parts of a large drum, since it may be used for comprises a pinion 33, connected to a driving pulley 34, the latter meshing with a gear 35 that is connected to cylinder or drum 31. 5 Gear 35 also drives gears 36 and 37, said gears 36 and 37 being fixed to the cylinders or drums 30, 29. For operating the wetting roll 16, an idle pinion 40 is driven by gear 37, and drives a pinion 41 connected with 10 said wetting roll. The companion roll 18 has a pinion 42 in mesh with a pinion 43 fixed on the shaft of said roll 16. Said gear 37 also meshes with a pinion 44 on the cylinder 28, and 44 meshes with an idle pinion 15 45 engaging a pinion 46 on the shaft of wetting roll 17. On said shaft is a pinion 47 to mesh with a pinion 48 on the shaft of its companion roll 18.

It will be understood that the paper is 20 made quite wet in order to permit it to be advanced at once to the bite of the corrugating rolls without the preliminary gathering of the paper into a fluted condition. If the paper is very absorbent, the described 25 addition of the water thereto expands the paper. This allows the corrugating to be performed without subjecting the paper to undue strain, particularly if the corrugations are relatively broad and shallow. 30 When paper is used that less readily absorbs water, it would be necessary to subject it more thoroughly to the dampening action, partly in order to expand it as much as possible, and also to render it slightly plastic or flexible before running it into the corrugating rolls.

The paper is sufficiently moistened and 35 softened by the described wetting apparatus to enable its fibres to yield readily to the fluting action of the rolls 28 and 29, which form the paper into corrugations and incidentally stretch the paper widthwise, and hence the necessity of a preliminary gathering of the web into a fluted condition before 40 entering the rolls may be avoided, the corrugations being impressed in the paper without the latter losing in width.

Some kinds of paper need to be wetted 45 only to a slight extent, and in that case the wetting may be performed by steam or by finely atomized water.

The paper is maintained in its corrugated condition as it is drawn around the second 50 revolving cylinder 29, and is further rolled or pressed between the latter and a third cylinder 30, thereby tending to deepen the corrugations and compact the paper in its laterally stretched corrugated condition. 55 This effect upon the paper is increased by its being drawn tightly upon the revolving grooved cylinder 30, the latter furthermore co-operating with the fourth grooved cylinder 31 to improve and perfect the corrugating of the sheet.

60 The cylinder 29 is preferably in the form

of a large drum, since it may be used for heating the paper, steam being supplied through a pipe 49. This heating by the drum 29 tends to diffuse the moisture generally throughout the paper, thereby bringing it into better condition for subsequent action by the corrugating rolls. The paper, moreover, by becoming heated has its subsequent drying action facilitated or hastened. The cylinder 30 is also used as a heating drum, 70 being supplied by a steam pipe 50, this cylinder augmenting the heating effect and also tending to dry out the paper.

The number of cylinders over which the paper is passed in order to roll it and dry 80 it to the extent desired, may be varied. It is preferred to wet the paper sufficiently to corrugate it without subjecting it to undue strain, and then to dry it partially or even render it substantially dry by the time it 85 reaches the hereinafter-described doctor-blade for crinkling, so that the paper at that juncture will be warm, so as to set the paper in its crinkled condition.

It will be understood that the corrugation 90 of the paper tends to stiffen it, so that it resists being bent to and fro around the cylinders 29, 30, 31, being bent first in one direction and then in the opposite direction, and then back to the first direction. For 95 aiding and overcoming this resistance, there may be provided upon the cylinders 29 and 30 endless belts, one of which is shown as applied to 30, although it will be understood that this represents belts upon 100 both said cylinders, to hold the corrugated web thereagainst. This endless belt is designated as 51, and runs from the introductory side to the delivery side of the cylinder, and then off and around rolls 52, 53 and 54 to 105 the introductory side again. The roll or pulley 53 may be used for tightening the belt, and for this purpose it may be mounted upon an adjustable arm 55. The belts hold 110 the corrugated web to the cylinders, or, in other words, co-operate with the cylinders to perform the desired work upon the paper, and also conduce to the better heating of the paper, inasmuch as it is kept in close contact with the heated surfaces of the drums.

Evaporation takes place between the cylinder and the belt with the result that the paper is wetted on both sides more thoroughly. The belt also causes the paper to absorb the moisture more thoroughly where double-ply paper or superposed webs are passed through the machine. Pulley 52 is driven by a gear 56 meshing with 35; and pulley 54 by a pinion 57 meshing with 36. 120

It will be understood that by the time the web has begun to advance around the cylinder 31, it is well compacted and heated; and, if desired, this cylinder 31 may also be supplied with heating means (not shown). A 125 grooved pressure roll 58 also co-operates 130

with the grooved drum 31, said roll meshing with the drum and being placed at the delivery part thereof, and being power-driven by means of a pinion 59 meshing with gear 35. This roll tends to draw the roll tightly to the periphery of the drum 31, and hence to overcome the stiffening or straightening tendency of the web, due to its fluted condition and arising partly from the bending of the web in a reverse direction from its bend around cylinder 30.

The roll 58 not only holds the web around cylinder 31 and co-operates with said cylinder in giving the final roll to the corrugations in the web, but also aids the cylinder in pressing the web against a stationary doctor-blade 60, which is fixed upon a cross-bar 61 mounted upon the machine frame 62, and is corrugated or grooved to fit the corrugations in the drum. By the co-operation of the rolls 31 and 58 and the doctor-blade, the paper is crinkled and passes at 63 onto a delivery belt 64.

To vary the sharpness and depth of the crinkling, the roll 58 may be mounted upon adjustable arms 65, whereby the position of the roll relatively to the doctor-blade may be varied. By adjusting the roll closer to the blade, the space between the roll and the blade is reduced so as to increase the difficulty of the paper in passing between them, and, owing to this added resistance, the paper becomes more crushed, or the crinkling becomes sharper and deeper; and by adjusting the roll away from the blade the opposite effect may be produced. The arms 65 are preferably mounted upon an axle 66 of the cylinder 31, so that the roll 58 will always retain its proper relationship to the surface of the drum 31.

In order to produce adjustment or movement of the roll 58 at predetermined intervals, so as to secure a regular variation in the characteristics of the crinkling and thereby produce an ornamental configuration of the product, the arms 65 may be oscillated by means of a revolving eccentric cam 67, upon which runs a roll 68, carried upon the end of an arm 69, which is rigid with arms 65. The cam may be rotated by means of an idle pinion 70, meshing with gear 35 and driving a pinion 71, which is connected to the shaft 72 of the eccentric cam. Therefore, once in each revolution of shaft 72, the roll 58 is given a complete oscillation, a spring 73 serving to swing the roll away from the doctor-blade 60 after the eccentric cam has forced the roll towards said blade. It will be understood, however, that roll 58 need not be made adjustable, either mechanically or otherwise in all cases.

Variations may be resorted to within the scope of the invention, and portions of the improvements may be used without others.

Having thus described my invention, I claim:

1. The combination of means for supporting a web of paper in the form of a supply roll, a pair of longitudinally corrugating rolls to which the paper is directly led from the supply roll, and means between the supply roll and the corrugating rolls for wetting the paper sufficiently to cause it to become plastic and stretchable, said rolls forming part of a set of pairs of corrugating rolls through which the paper is led, and certain rolls in said set being provided with heating means.

2. The combination of means for supporting a web of paper in the form of a supply roll, a pair of longitudinally corrugating rolls to which the paper is directly led from the supply roll, and means between the supply roll and the corrugating rolls for wetting the paper sufficiently to cause it to become plastic and stretchable, said rolls forming part of a set of pairs of corrugating rolls through which the paper is led, one of the rolls in said set being provided with heating means to diffuse the moisture evenly throughout the web.

3. The combination of means for supporting a web of paper in the form of a supply roll, a pair of longitudinally corrugating rolls to which the paper is directly led from the supply roll, and means between the supply roll and the corrugating rolls for wetting the paper sufficiently to cause it to become plastic and stretchable, said rolls forming part of a set of pairs of corrugating rolls through which the paper is led, one of the rolls in said set being provided with heating means to diffuse the moisture evenly throughout the web, and another of said rolls being provided with heating means to aid in drying the paper.

4. The combination of means for supporting a web in the form of a supply roll, a pair of corrugating rolls to which said web is directly led, means between said corrugating rolls and supply roll for wetting the paper, and means for transversely crinkling the corrugated web.

5. The combination of means for supporting a web of paper in the form of a supply roll, a pair of longitudinally corrugating rolls to which the paper is directly led from the supply roll, means between the supply roll and the corrugating rolls for wetting the paper sufficiently to cause it to become plastic and stretchable, said corrugating rolls being formed to stretch the paper laterally while rolling wide corrugations therein, and means for crinkling the corrugated web.

6. The combination with means for supporting a supply roll, of corrugating rolls for rolling wide corrugations in the paper

and incidentally stretching the same, wetting rolls upon opposite sides of the web between the corrugating rolls and supply roll, and means for supplying water to said wetting rolls.

7. The combination with means for supporting a supply roll, of corrugating rolls for rolling wide corrugations in the paper and incidentally stretching the same, wetting rolls upon opposite sides of the web between the corrugating rolls and supply roll, and means for supplying water to said wetting rolls, said water-supplying means comprising troughs and rolls immersed in the troughs and running in contact with the said wetting rolls.

8. The combination with means for supporting a supply roll, of corrugating rolls for rolling wide corrugations in the paper and incidentally stretching the same, wetting rolls upon opposite sides of the web between the corrugating rolls and supply roll, and means for supplying water to said wetting rolls, means being provided for regulating the pressure of the wetting rolls against the paper.

9. The combination with means to supply a web of paper, of means to wet the paper, two rolls between which the wet paper is corrugated longitudinally of the web and incidentally stretched transversely, and a third roll to co-operate with one of said rolls to subject the paper to further corrugating action.

35 10. The combination with means to supply paper, of means to wet the paper, two rolls between which the wet paper is corrugated and incidentally stretched, a third roll to co-operate with one of said rolls to subject the paper to further corrugating action, and means to crinkle the paper transversely.

45 11. The combination with means to supply paper, of means to wet the paper, two rolls between which the wet paper is corrugated and incidentally stretched, a third roll to co-operate with one of said rolls to subject the paper to further corrugating action, and a fourth roll to co-operate with the third roll in still further rolling the corrugations in the paper.

50 12. The combination with means to supply paper, of means to wet the paper, two rolls between which the wet paper is corrugated and incidentally stretched, a third roll to co-operate with one of said rolls to subject the paper to further corrugating action, a fourth roll to co-operate with the third roll in still further rolling the corrugations in the paper, and means for co-operating with said fourth roll to crinkle the paper transversely.

55 13. The combination with means to supply a web of paper, of means to wet the paper, first and second rolls between which the wet paper is corrugated longitudinally

of the web and incidentally stretched transversely, a third roll to co-operate with one of said rolls to subject the paper to further corrugating action, said second roll being in the form of a drum, and means to heat the drum.

14. The combination with means to supply a web of paper, of means to wet the paper, first and second rolls between which the wet paper is corrugated longitudinally of the web and incidentally stretched transversely, and a third roll to co-operate with one of said rolls to subject the paper to further corrugating action, said second and third rolls being in the form of drums, and both being provided with heating means.

15. In a paper-crinkling machine, the combination with a cylinder and a doctor-blade or device to co-operate therewith, of a pressure roll or device to hold the paper against the cylinder in the vicinity of the doctor-blade, and means to adjust said roll towards and away from the doctor-blade.

16. In a paper-crinkling machine, the combination with a cylinder and a doctor-blade or device to co-operate therewith, of a pressure roll or device to hold the paper against the cylinder in the vicinity of the doctor-blade, and means operatively connected to said cylinder for moving said roll towards and away from the doctor-blade.

17. In a paper-crinkling machine, the combination with a cylinder and a doctor-blade or device to co-operate therewith, of a pressure roll or device to hold the paper against the cylinder in the vicinity of the doctor-blade, and revoluble cam mechanism connected to said cylinder to move said roll towards and away from the doctor-blade.

18. In a crinkling machine, the combination with a cylinder, a doctor-blade, and a roll to press the paper against the cylinder in the vicinity of the doctor-blade, of means for automatically effecting variations in the relationship of the roll, doctor-blade and cylinder.

19. The combination of means for supporting a web of paper in the form of a supply roll, a set of longitudinally corrugating rolls to which the paper is directly led from the supply roll, means between the supply roll and the corrugating rolls for wetting the paper sufficiently to cause it to become plastic and stretchable, said corrugating rolls being formed to stretch the paper laterally while the rolling wide corrugations therein, a doctor-blade to co-operate with the final roll to crinkle the web, and a corrugated or grooved roll to run upon said final roll in the vicinity of the doctor-blade.

20. The combination of means for supporting a web of paper in the form of a supply roll, a set of longitudinally corrugating rolls

- to which the paper is directly led from the supply roll, means between the supply roll and the corrugating rolls for wetting the paper sufficiently to cause it to become plastic and stretchable, said corrugating rolls being formed to stretch the paper laterally while rolling wide corrugations therein, a doctor-blade to co-operate with the final roll to crinkle the web, and a corrugated or grooved roll to run upon said final roll in the vicinity of the doctor-blade, the last-mentioned roll provided with means whereby it may be adjusted towards and from the doctor-blade.
21. In a crinkling machine, the combination of a cylinder, a doctor-blade, a roll to press the paper against the cylinder in the vicinity of the doctor-blade, arms whereon said roll is journaled, said arms mounted to rock upon the axis of said cylinder, and means to rock said arms.
22. In a crinkling machine, the combination of a cylinder, a doctor-blade, a roll to
- press the paper against the cylinder in the vicinity of the doctor-blade, arms whereon 25 said roll is journaled, said arms mounted to rock upon the axis of said cylinder, a power-driven cam to rock said arms in one direction, and a spring to return them.
23. The combination with a set of elements co-operating to crinkle a sheet transversely, of mechanism for automatically effecting variations in said set of elements, to secure a regular variation in the characteristics of the crinkling. 30
24. The combination with means for corrugating a web longitudinally, a set of elements including a doctor-blade, a corrugating crinkling cylinder, and a pressure roll for producing zigzag crinkling transversely 35 of the web, of mechanism for automatically effecting variations in said set of elements, to secure a regular variation in the characteristics of the crinkling. 40

WILLIAM A. LORENZ.
